CLAIM

The ornamental design for a pad for foot pedal, as shown and described.

DESCRIPTION

FIG. 1 is a right, front, perspective view of a pad for foot pedal showing my new design;

FIG. 2 is a right, front, perspective view thereof, the design shown in the environment of a foot pedal;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side view thereof; and,

FIG. 8 is a right side view thereof.

The broken lines represent environmental subject matter that forms no part of the claim design.
